MACHINE FOR COVERING ARTICLES

Alexis E. Ushakoff, Beverly, Mass., assignor to
United Shoe Machinery Corporation, Flemington, N. J., a corporation of New Jersey

Application June 9, 1942, Serial No. 446,395

26 Claims.

(CL 12—49.1)

This invention relates to machines for covering articles and is herein illustrated as embodied in a machine particularly adapted for use in covering heels.

The general object of the invention is to provide a machine for rapidly covering articles by the use of covers made of a shrinkable material. In accordance with one feature of the invention there is provided a carrier, a plurality of work-holders which are all alike, a plurality of stations where certain operations, such as shrinking the cover about the article, are performed, means for producing intermittent relative movements between the carrier and the stations to cause the stations to be aligned with the work-holders, and means for producing relative movements of reciprocity in the pauses between the intermittent aligning movements to cause various operations to take place at the same time at the various stations.

In the illustrated machine each work-holder picks up a heel at the first station, places it in a shrinkable cover at the second station, lowers the heel and cover into a shrinker at the third station, and trims off the surplus material from the shrunken cover at the fourth station. The machine runs continuously, the heels and the covers being presented to the machine by the operator at the first and the second stations respectively.

This and other features of the invention, including certain details of construction and combinations of parts, will be described as embodied in an illustrated machine and pointed out in the appended claims.

Referring now to the accompanying drawings, Fig. 1 is an elevation of the first station with a work-holder above it, the work-holder being in position to descend and pick up a heel;

Fig. 2 is an elevation of the second station where a heel is placed in a cover, and the mouth of the cover is clamped to a work-holder. In the position of parts shown, the work-holder occupies its uppermost position after having descended to place the heel in the cover, and then risen with the cover clamped to the work-holder;

Fig. 3 is an elevation of the third station where a cover is caused to shrink about a heel. In the position of parts shown, a work-holder occupies its uppermost position after having descended, to cause the heel and cover to enter the shrinking oven, and then risen with the heel and the shrunken cover;

Fig. 4 is an elevation of the fourth station where the surplus material is trimmed from the shrunken cover. In the position of parts shown,

a work-holder with the heel and its shrunken cover is in its uppermost position ready to descend;

Fig. 5 is a view partly in elevation and partly in vertical section of the first station, a heel being shown as having been engaged by the picker of a work-holder;

Fig. 6 is an elevation viewed from the right of Fig. 5, showing some of the same parts as are shown in said figure;

Fig. 7 is a perspective of a finished, covered heel;

Fig. 8 is a plan of the support for a heel at the first station;

Fig. 9 is a view principally in elevation of the second station, a cover being shown into which a heel is about to be lowered by a work-holder;

Fig. 10 is a view principally in elevation showing more particularly the position of parts near the end of the downward movement of a work-holder;

Fig. 11 is a detail in perspective showing more particularly one of the two cams which serve to swing out the clamping fingers;

Fig. 12 is a view similar to Fig. 10 but showing a work-holder in its lowermost position;

Fig. 13 is a detail in elevation of the same parts shown in Fig. 11;

Fig. 14 is a view principally in vertical section showing a work-holder with a heel and its cover above the third station where the shrinking takes place;

Fig. 15 is a view partly in elevation and partly in vertical section showing the lower portion of a work-holder with a heel and its cover in the shrinking oven before the heel and most of the cover are moved up with respect to the sleeve of the work-holder to which the mouth of the cover is clamped;

Fig. 16 is a view similar to Fig. 15 but showing the positions of parts after the heel and most of the cover have been moved up;

Fig. 17 is a view partly in elevation and partly in section showing the lower portion of a work-holder with a heel and its shrunken cover;

Fig. 18 is a view principally in elevation of the shrinking station with a work-holder in its lowermost position and about to move up;

Fig. 19 is a detail, viewed from the right of Fig. 18, partly in section and partly in elevation, showing more particularly one of the toggle mechanisms which are straightened at the shrinking station;

Fig. 20 is a detail principally in elevation of a latch which cooperates with a slide rod in

straightening the toggle mechanisms and in turning a valve to apply suction to the interior of a cover.

Fig. 21 is a view partly in section and partly in elevation of part of the mechanism shown in Fig. 18 but on a larger scale and taken from the opposite side of said mechanism;

Figs. 22 and 23 are details in elevation showing successive positions of parts of a portion of the mechanism which operates to straighten the toggle joints and to apply suction to the interior of a cover;

Fig. 24 is an elevation showing part of the fourth station where the cover is trimmed, the parts of the mechanism of a work-holder being in position to break the toggle joints which were straightened at the shrinking station and to cut off the suction;

Fig. 25 is a view principally in vertical section of the fourth station showing the parts in the positions which they occupy when a work-holder has reached its lowermost position at the trimming station and is about to rise and cause the severed surplus material at the upper portion of the cover to be stripped off from the work-holder. In order not to confuse the showing in the other figures, the stripping mechanism has been shown only in Figures 25 and 28;

Fig. 26 is an elevation of the upper part of the machine;

Fig. 27 is a detail, principally in section, showing more particularly how the projection at the bottom of the cover is cut off;

Fig. 28 is a detail in elevation showing how the clamping fingers are swung out at the trimming station to release the cover;

Fig. 29 is a detail principally in elevation of the two clutches on the shaft which is clutched to the driving shaft;

Fig. 30 is an elevation partly in section and partly in elevation of the lower part of the machine, showing the driving mechanism. This figure is complementary to Fig. 26, the two figures taken together being a view of the whole machine;

Fig. 31 is a detail looking down from above the machine, and showing more particularly the mounting of the carrier for the work-holders on the rotary and reciprocating shaft, and the stationary plate on the edge of which the rolls of certain latches run;

Fig. 32 is a detail principally in vertical section of a modification in which the suction conduits in the radial arms are at all times in communication with the suction conduits leading into the work-holders; and

Fig. 33 is a detail in perspective and on a greatly enlarged scale of one member of a clutch which is rigid with the hub of a gear.

The illustrated machine has four stations which are arranged radially about a center and are spaced apart ninety degrees; and located above them are four work-holders which are caused to cooperate successively with them. The four work-holders are mounted on the outer ends of radial arms, the inner ends of which are fast to a carrier secured to the upper end of an upright shaft, the axis of which is the center about which the stations, as well as the work-carriers, are arranged. The work-holders, when the machine is at rest, are each located above a station. This upright shaft, with its carrier and the four work-holders, is rotated intermittently, to cause each work-holder to register with the next succeeding station, and is intermittently recipro-

cated during the pauses between the intermittent movements of rotation, to cause each work-holder first to be moved down into cooperative relation with the station with which it is in register and then to be moved up again.

At the first station (Fig. 1), where the operator has placed a heel 100 upon a support, the work-holder descends, forces a picker into the attaching face of the heel and rises, thereby lifting the heel with it. In Fig. 1 the work-holder is in register with the first station and is about to descend. Rotation of the carrier brings the work-holder with its heel above and in register with the second station (Fig. 2). Here the operator has placed a thin-walled cover 200 with its mouth facing upward in position to receive the heel, said cover being made of a material which will shrink greatly when exposed to the action of a shrinking agent, such for example as heat.

20 The work-holder descends to locate the heel in proper position in the cover, and the mouth of the cover is clamped at separated points to the work-holder which then rises. In Fig. 2 the work-holder, with the mouth of the cover 200 25 clamped to it and with the heel held in proper position in the cover, is in its uppermost position. At the third station (Fig. 3) there is a shrinker, herein shown as an oven, having its open mouth facing upward into which the work-holder lowers the heel and its cover, the work-holder pausing in its lowermost position, as it does at all the stations, for a short interval which may be of the order of three seconds. The heat presently softens the cover which begins to 30 shrink. Just after the work-holder starts its upward movement, a partial vacuum is created in the cover, and this partial vacuum, in conjunction with the heat, causes the cover to be drawn and shrunk tightly about the heel. In 35 Fig. 3 the work-holder has descended into the oven and then risen to its uppermost position, the cover having been shrunk about the heel. At the fourth station (Fig. 4) the descent of the work-holder causes the surplus cover material to 40 be trimmed from the attaching face of the heel and also causes the small projection 390 at its bottom to be cut off. This projection, in the illustrated cover, is part of the sprue which resulted when the cover was molded. In Fig. 4, 45 the work-holder is in its upper position ready to descend. When it has descended and the trimming and cutting referred to above have taken place, an attendant removes the covered heel which has the appearance shown in Fig. 7.

50 Referring to Fig. 26, which shows in elevation the upper part of the machine, the work-holders are mounted at the lower ends of hollow vertical rods 41, the upper ends of said hollow rods being clamped by pinch screws 43 in split blocks 45 55 which have sockets to receive the outer ends of horizontal radial arms 47, said arms being fastened thereto by set screws 49. The inner ends of the arms 47 are fastened to a carrier 51 (Fig. 31) fixed to the upper end of an upright shaft 53 which, as will presently be explained in detail, is intermittently rotated through ninety degrees and is reciprocated in the pauses between said intermittent rotations. It may be noted here that the upright shaft 53 (Fig. 30) has a port 55 in its center, the lower end of which is in communication with one end of a rubber pipe 57, the other end of which is connected to the inlet of a pump 58; and that this port 55 at its upper end is at all times in communication with 60 the central ports in the radial arms 47 (Fig. 26).

at the outer ends of which the vertical rods 41 are mounted. The partial vacuum, created by the pump and indicated by the gage 60, is used, however, only at the shrinking station and is rendered effective at that station by valve mechanism which is located at the outer end of each arm. This mechanism will be described in connection with the description of what takes place at that station.

Mounted for free rotation about the axis of the rotatable and reciprocable shaft 53, at the upper end of which the carrier 51 and the radial arms 47 are supported, is a spider 59 (Fig. 26) having four arms spaced ninety degrees apart; and each arm has at its outer end two lined vertically spaced bearings through which are slideable the vertical rods 41 at the lower ends of which the work-holders are mounted. This spider is rotated intermittently by mechanism which will be described later and moves the work-holders with it, but remains stationary when the shaft 53 and the work-holders are vertically reciprocated.

Referring to Figs. 5, 6 and 8, the first station and the picking up of the heel will be described. At this station a heel 100 is placed by the operator upon a stationary plate 73 which is slidably mounted so as to be adjustable upon a support 75 and is held in adjusted position by a set screw 77 and a lock nut 79. The support 75 is pinned to the upper end of a rod 81 vertically slideable in spaced bearings 82 in a stationary part of the machine and held from rotation by the inner end of a screw 83 which extends into a vertical slot formed in the rod 81. A stop-collar 85, adjustably fastened in position on the rod by a set screw 87 and resting upon the lower one of the spaced bearings provides means for adjusting the rod vertically. On the plate 73 there is an adjustable stop or gage for the back of the lower end of a heel, said gage being in the form of a small plate 89 having elongated slots through which pass screws 91 which are threaded into the plate. An adjustable side gage, in the form of a small plate 93 slidably mounted on a plate 97 and having an elongated slot, is adjustably held in place by a screw 95 on the plate 97 which is fastened to the larger plate 73. An opposite side gage 99 is carried on a horizontal stem in a bearing in a second small plate 102, which is fastened to the larger plate 73 and is continually urged to move toward the side gage 93 as far as a nut 104 threaded on the stem will permit. The two side gages 93, 99 have their forward working-engaging faces flaring away from each other to facilitate pushing a heel 100 into place. It will be noted that the plate 73 is adjustable on its support 75 in a path which extends in the same general direction as that of the path of rotation of the carrier, being held in adjusted position by the set screw 77, and that the support 75 may be adjusted vertically by means of the adjustable collar 85. In addition, the position in which the operator places the heel on the plate 73 may be varied lengthwise of the plate by adjusting the back gage 89, and transversely of the plate by adjusting the side gage 93. By means of these adjustments the heel may be located in proper position to receive in its attaching face the picker, presently to be described, of a work-holder.

The work-holders are all alike, and the one shown in Fig. 5 will now be described. Threaded upon the enlarged lower end of the hollow rod 41 is a sleeve 101 having slideable in it a plunger

103, the purpose of which is to hold four clamping fingers 105, with the toothed members 107 at their lower ends, in position to clamp the mouth of a cover to the work-holder at station 5 number two, the stems of the toothed members 107 being adjustably held by pinch screws 108. There are four of these clamping fingers each pivoted at 109 to ears on the sleeve 101 and having short arms at or near their upper ends which 10 extend through slots in the sleeve 101, the rounded extremities of said arms being received in an annular groove in the plunger 103. A spring 111, the lower end of which rests upon a shoulder on a hollow member 113, threaded into the 15 lower end of the sleeve 101, normally holds the plunger 103 in the position shown. Vertically slideable in the hollow rod 41 is a small vertical rod 115 having in its center a small port 117. This rod 115 is raised and suction is applied 20 through the small port at station number three, where the shrinking of the cover takes place. The lower end of the small rod 115 is enlarged and the rod is normally held down, as shown, by a compression spring 118. In vertical sockets, 25 arranged in a substantially horseshoe-shaped pattern in this enlargement are small compression springs 119 which act upon the tops of the stems of a sectional trimmer in the form of a plurality of blades or cutters 121, said cutters operating 30 at the fourth station to trim the surplus cover material from the shrunken cover. A picker 123, having two prongs as shown in Fig. 6, is carried by a small block 125 which is vertically slideable in the enlarged lower end of the small rod 115, 35 said block being normally held by a spring 127 in its lowermost position, which is determined by a stop member carried by the enlargement.

The entire construction of the work-holders, all of which are alike, has been described above, 40 and reference has been made to certain operations in which the work-holders take part at succeeding stations. At the first station the whole work-holder is reciprocated, but there is no separate movement of any of its parts, except 45 that the picker 123 may yield somewhat if necessary against the force of the spring 127, the spring 118 being stronger than the spring 121. At the first station, then, the work-holder descends to force the points of the picker into the heel, as shown in Figs. 5 and 6, and then rises carrying the heel with it.

Referring now to Figures 9 to 13, there is shown the second station and the manner in which a work-holder places a heel in a cover. 55 The operator places the bottom of a cover 200 in a holder 129 in the form of a sort of shallow cup having in its bottom an opening to receive the small projection 300, said holder being integral with a plate 131 which is slidably adjustable in a dovetailed slot in a support 133 and is held in adjusted position by a set screw 135. The support 133 is fast to the upper end of a rod 137 which is vertically slideable in lined bearings 139. The rod is held from rotation by a set screw 141 threaded through a wall of the upper bearing, the end of said set screw extending into a vertical slot 143 in the rod; and the rod may be adjusted vertically by changing the position upon it of a collar 145 held in place by a set screw 147, said collar resting upon the lower bearing 139. The rod 137 is so held from turning by the set screw 141 that the plate 131 extends in the same general direction as that of the path of rotation of the work-holders. 60 Located above the support for the cover is a

stationary member 149 having the shape of a segment of a hollow cylinder into which the work-holder descends, said member being supported by the frame of the machine. The purpose of this member is to support cams which, during the descent of the work-holder, cause the clamping fingers 105 to swing to open position, as shown in Fig. 10, and then permit the fingers to close upon the cover, as shown in Fig. 12, and to remain in closed position when the work-holder rises. There are two of these cams located 180° apart which act upon two diametrically opposite clamping fingers; and adjacent each cam as well as in the back part of the wall of the member 149 there is a vertical slot or opening to permit the fingers 105 to swing out. It will be noted that swinging out two diametrically opposite clamping fingers 105 (Fig. 5) provides a convenient way of raising the slide block 103 and thereby causing all four clamping fingers to swing out. Since the two cams are alike and mounted in substantially the same way upon the hollow member 149, only one cam and its mounting will be described in detail.

Referring more particularly to Fig. 11, each cam comprises a block 151 having an inclined cam surface 153. This block is integral with a stem 155 which is fast to a small rock-shaft 157 mounted in spaced ears on the hollow member 149 and is urged at all times to occupy the position shown by a spring 159, the middle part of the spring being coiled about the rockshaft 157, and the two ends engaging respectively the wall of the hollow cylinder and a pin 161 which is carried by a small arm 162 fast to the rockshaft. In this position, a locality on the under side of the stem 155 is held against the rim of the hollow member 149, and the cam cannot swing down. Above the cam surface 153 there is shown the lower end of a clamping finger 105, said finger carrying two vertically spaced small pins 163. When the work-holder with its heel 100 descends, these pins, one after the other, engage the inclined cam surface 153, and the finger 105 is swung to open position and remains in open position until the uppermost pin has slid down the incline and entirely off from the block 151. By this time the heel 100 has been properly located in the cover 200, as shown in Fig. 12, and the finger 105 is swung in by the spring 111 and plunger 103 (shown in Fig. 5) to clamp a portion of the mouth of the cover to the sleeve 101 of the work-holder (Fig. 12). When the work-holder rises, carrying the clamping fingers 105 with it, such upward movement is permitted without disturbing the clamping position of the clamping fingers since the small horizontal pins 163 of the fingers engage the under-side of the cam blocks 151 (Fig. 13) and swing them up out of the way against the force of the springs 159.

One of the intermittent movements of rotation of the carrier brings a work-holder with a heel 100 into position above a hollow cover 200 on its holder 129, as shown in Fig. 9. During the descent of the work-holder to locate the heel in the cover, the clamping fingers are swung out to open position (Fig. 10) and are held open until the heel has reached its lowermost position, whereupon the fingers clamp the mouth of the cover to the sleeve 101 of the work-holder at spaced localities, as shown in Figure 12. When the carrier with its heel and cover rises, the cams are swung out, but return to their normal positions as soon as the pins 163 on the clamping fingers 105 have ceased to engage the cams. It

should be noted that the heel, still engaged by the picker 123 (Fig. 5), is held above the bottom of the cover, it being desirable that the heel should be so held independently of the cover during the subsequent shrinking operation. The hollow member 149 is open at the front, that is, when viewed as in Figs. 9, 10, 12 and 13, to permit the operator to place a cover 200 on its support 129.

Referring now to Figs. 14 to 17, the shrinking station and what takes place there will be described. Fig. 14 shows, principally in vertical section and at right angles to the showing in Fig. 12, the lower portion of a work-holder and the positions which its parts occupy when a heel has been properly located in the cover, and the work-holder has been raised and brought into position above the third station where the shrinking of the cover is to take place. Figs. 15 to 17 show what happens at this third station. The work-holder with its heel and cover is lowered into a shrinker in the form of an open-mouthed oven 165 which is heated to a suitable temperature, which may be in the neighborhood of 800° F., by resistance coils 167, 169, this temperature depending upon the thickness of the cover and the material of which it is made. The current supplied to the coil 167 may be varied by turning the control member 171 (Fig. 18) of a variable autotransformer (not shown) a second transformer (also not shown) the rotatable control member of which is indicated at 173, being provided for the coil 169. The work-holder descends into the position shown in Fig. 15. During the pause which occurs when the carrier is in this position, the heat softens the cover and the cover begins to shrink. It is impossible to state exactly the extent of the shrinking, but probably the cover shrinks to the extent shown in Fig. 15, the bottom of the cover being drawn up firmly against the bottom of the heel. In order to permit the cover to conform to the concave surfaces of the heel as well as to aid it in so doing and to permit part of it to be drawn over the margin of the attaching face of the heel, the heel is lifted a short distance with respect to the cover so as to produce a slack in the walls of the cover, and at the same time a partial vacuum is produced in the cover so as to assist the shrinking in conforming the cover to the heel. Fig. 16 shows the heel lifted and the walls of the cover slack or loose. The heat and the partial vacuum now act to conform the cover to the heel as shown in Fig. 17, a portion of the wall of the cover having been drawn in a sort of loop over the attaching face of the heel.

The heel is lifted from the position shown in Figs. 14 and 15 to that shown in Figs. 16 and 17 by pulling up the rod 115 in the enlarged lower end of which the picker 123 is held; and the partial vacuum in the cover is created at the same time by applying suction through the port 117, the lifting of the heel and the application of suction taking place during the first part of the upward movement of the work-holder. The suction, when first applied, is ineffective because the mouth of the cover is clamped at separated localities; but the instant the cover shrinks closely about the lower end of the sleeve 101, a considerable partial vacuum is formed in the cover.

Referring now more particularly to Figs. 18 to 24, the manner in which the heel is lifted and suction applied to the interior of the cover will

be described. The suction is applied by turning a rotary valve 175 to the position shown in Fig. 21 in which position a port 177 in the horizontal arm 47, through which suction is always being applied, is in communication, through a rubber tube 176, with the port 117 in the small vertical rod 115. The valve has projecting from its farther end, as viewed in Fig. 21, a pin 178 (Figs. 22 and 23) to which is fastened the hub of a segmental gear 179 which meshes with another segmental gear 181, said last-named gear being fast to a leg of a member, of inverted U-shape, 183, the downwardly extending legs of which are rotatably mounted for swinging movement about a small rockshaft 185 mounted in an upstanding ear on the block 45, said ear being received between the legs of the inverted U-shaped member 183. This member has integral with it an arm 186 of the shape best shown in Figs. 22 and 23, said arm having a fork at its end provided with a slot 187. This slot has an approximately vertical portion and a portion at an angle to said approximately vertical portion. Extending into the slot is a pin 189, which occupies the position shown in Fig. 22 when the valve 175 (Fig. 21) is closed, and the position shown in Fig. 22 when the valve is open. The pin 189 is carried by the enlarged rounded upper end of a rod 191 which is vertically slidable in spaced bearings 193 carried by one of the arms of the four-armed rotary spider 59. As has been explained, the block 45 which carries all the parts just described except the spider 59, is reciprocated vertically at each station; but such reciprocation causes no turning of the normally closed valve 175 to its open position shown in Fig. 21 except at the shrinking station. In order to cause the valve 175 to be turned to open position during the first part of the upward movement of the carrier at the shrinking station, while the cover with the heel in it is still being subjected to heat, the slide rod 191 is held stationary for a moment while the block 45 is moving up. Before this differential movement starts the parts are in the positions shown in Fig. 22, with the valve 175 closed, and when it has finished the parts are in the positions shown in Fig. 23 wherein all the parts there shown, except the rod 191 and the parts carried by it, have moved up. Thereafter the block 45 and everything carried by it, including the rod 191, moves up; but, during the differential movement referred to above, the arm 183 has been swung from the position shown in Fig. 22 to that shown in Fig. 23, and the valve 175 has been turned into the open position shown in Fig. 21 to apply suction through the vertical port 117 in the small rod 115 to the interior of the cover which, with a heel in it, is still in the oven.

The rod 191 is moved down when the carrier moves down, by reason of the position of the pin 189 (Fig. 22) in the angular slot 187. It is held momentarily from upward movement from its lowermost position at the shrinking station by a latch 195 (Figs. 18 and 20) which engages a small block 196 adjustably fastened to the rod 191. This latch (Fig. 20) has its hub fast to a small rockshaft 197 carried by an arm of the spider 59, said shaft extending through to the other side of said arm and having attached to its far end the hub of a substantially upright arm 199 having at its upper end a horizontal pin 201. This pin extends into a vertical slot in an extension which forms part of a pin 203, said pin being mounted for horizontal sliding movement in a

socket in a member 205 which is rigid with the spider 59. The pin is continually urged outwardly (to the left as viewed in Figs. 18 and 20) by a compression spring 207. It is held to the right during all of the reciprocation of the carrier, except for a very short interval by contact of its end with a rod 209. This rod, however, has a short portion of reduced diameter and when this is opposite the end of the pin 203 the pin is moved to the left (Fig. 21) by the spring 207, thereby swinging the latch 195 into position to engage the block 196. The rod 209 is moved down and then up during the last part of the downward movement of the head and the first part of its upward movement. To this end the rod 209 is mounted for vertical reciprocation in spaced bearings in the spider 59 and is continually urged upward by a tension spring 211 as far as a stop 213 (Fig. 18), adjustably fastened to the rod, will permit, said spring being fastened at its upper end to the spider 59 and at its lower end to an adjustable collar 215 on the rod. When the carrier 51 and the block 45 descend, a collar 217 (Fig. 21), adjustably fastened to the rod 41, strikes the head of a small screw-bolt 219, screwed into the upper end of the rod and held in adjusted position by a lock nut 221, and moves the rod down. As soon as the rod 209 has descended far enough to permit the pin 203 to be moved to the left into engagement with the portion of reduced diameter of the rod, the latch 195 is swung to the left into operative position and remains in that position until after the block 196 has moved past it (Fig. 18). When now the carrier 30 rises, the latch 195 engages the block 196 and holds the rod 191 from upward movement until the rod 209 is permitted by further upward movement of the block 45 to be pulled up by the spring 211 far enough to cause the end of the pin 203 to run off from the lower end of the portion of reduced diameter of the rod 209 onto a portion of the full diameter, as shown in Fig. 20, whereupon the latch 195 is swung to the right to release the block 196 and permit the rod 191 to move up with the carrier 51 and block 45. As has been explained above, it is during the time that the rod 191 is held from upward movement that the carrier is moving upward, that the parts are moved from the positions shown in Fig. 22 to those shown in Fig. 23, and suction is applied to the interior of the cover while said cover, with a heel inside it, is in the oven. The latches 195 are capable of operating in the manner described above only at the shrinking station because of the following construction. Each latch 195 has a downwardly extending tail carrying at its lower end a small rod 222 which, as the spider 59 is rotated, runs upon the edge of a stationary plate 224 (Fig. 31), said roll being held against the edge of the plate by the action of the compression spring 207. The plate 224 (Figs. 26 and 30) is fastened to the top of the frame of the machine by screw-bolts, and its edge (Fig. 31) is circular in outline except at the shrinking station where it is cut away as indicated at 226. The rolls 222, at the lower ends of the tails of the latches 195, are thus held out except at the shrinking station, and the latches 195 are consequently held in inoperative positions except at that station.

At the same time that the suction is applied to the interior of the cover, the small vertical rod 115 is pulled up into the position shown in Fig. 16 to produce slack in the wall of the cover so that the upper part of the wall may be drawn over the attaching face of the heel, as shown in Fig. 17;

and this pulling up of the small vertical rod 115 is caused by the same differential movement between the rod 191 and the head which caused the suction to be applied. The small vertical rod 115 (Fig. 21) is threaded at its upper end to receive an adjusting nut 223, said nut being located in a horizontal slot in a small elongated block 225 (see also Fig. 26) so that, when the nut is turned, the rod 115 is adjusted vertically with respect to the block. This block is normally in lowered position in which its underside rests upon the upper surface of the block 45. It is raised so as to pull up the rod 115, and thereby pull the heel up with respect to the sleeve 101 of the work-holder, during the first part of the upward movement of the carrier 51 (Fig. 31) from its lowermost position, this pulling up of the rod 115 in its hollow rod 41 being brought about, as has been stated, by holding the slide rod 191 stationary for a short interval during the upward movement of the carrier.

To this end the small elongated block 225 is rotatably mounted on a small horizontal spindle 227 which passes through the block and projects from either end, and these projecting ends are supported respectively by two toggle joints, one on each side of the block 45. Referring now to Fig. 24, which shows the opposite side of the mechanism from that shown in Fig. 18, the projecting end of the spindle 227 extends through a slot in an upper toggle lever 229, the position of the end of the spindle in the slot being capable of being varied by turning an adjusting screw 231. A nut 232 is provided for locking the screw in position. The mechanism about to be described is duplicated at the other end of the spindle 227 as appears in Fig. 18. Referring again to Fig. 24, the upper toggle lever 229 is slidably received in a forked member 233 through the upper closed end of which the screw 231 is threaded. Referring to Fig. 19, the stem of the screw 231 has a portion of reduced diameter which extends through the upper portion of the toggle lever 229 into the slot therein, and on the lower end of the stem of the screw is fastened a collar 235 which rests upon the upper side of the horizontal spindle 227. In contact with the lower side of this spindle is a pin 237 which is carried at the lower ends of the arms of the forked member 233. The lower end of the upper toggle member 229 is pivoted at 239 (Fig. 24) to the upper end of a lower toggle member 240, which is pivoted about a pin 241 carried by the block 45, the end of the spindle 227 and the pin 241 being connected by a tension spring 243 which tends, when permitted to do so, to aid in breaking the toggle joint, as shown, in which position the small vertical rod 115 is in its lowermost position. The toggle joint may be straightened against the force of the spring by causing a link 245 to push the pivot 239 to the right. This link is pushed to the right by the downwardly extending arm of a bell-crank lever 247, the hub of which is pinned to the small rockshaft 185, the lower end of the vertical arm of the bell-crank lever being pivoted at 249 to one end of the link 245. Referring now to Fig. 18, which shows the other end of the small rockshaft 185, there is fast to that end of said shaft the hub of a bell-crank lever 251, the substantially horizontal arm of which is swung down by the action upon it of the pin 189 when the slide rod 191 is held stationary and the carrier 51 for the blocks 45 moves up. When this occurs, the inverted U-shaped member 183 is swung clockwise as viewed

in Fig. 18, as has been explained, to turn the valve 175 to the open position shown in Fig. 21; and at the same time the substantially horizontal arm of the bell-crank lever 251 (Fig. 18), is swung down to rock the small shaft 185 clockwise. As has been stated above, the toggle mechanism shown in Fig. 24 is duplicated on the other side of the block 45. This duplicate mechanism is shown in Fig. 18, and the parts are indicated by the same reference numerals used in Fig. 24 but increased by three hundred. When the substantially horizontal arm of the bell-crank lever 251 is swung down, not only is the small shaft 185 rocked but the downwardly extending arm of this bell-crank lever 251 is swung to the left (Fig. 18), and consequently the link 545 is caused to straighten the toggle levers 529, 540 at the same time that the link 245 (Fig. 24), by the swinging of the bell-crank lever 247, straightens the toggle levers 229, 240. The horizontal arm of the bell-crank lever 247 (Fig. 24) has a horizontal slot to receive a pin 253 in the upper end of a vertical slide rod 255 which is mounted, like the slide rod 191, for vertical sliding movement in bearings in the spider 59. Referring again to Fig. 18, the downwardly extending arm of the bell-crank lever 251 is provided with a small curved slot to receive a pin 257 carried by the block 45, the pin serving as a stop to limit the extent of swinging movement of the downwardly extending arm.

It will be noted that, by turning the nut 223 (Fig. 21), the lowermost position of the rod 115 with respect to the hollow rod 41, and hence (Fig. 14) the distance below the sleeve 101 of the work-holder at which the heel is held, may be varied; and that, by turning the adjusting screws 231, 531 (Figs. 24 and 18), its uppermost position may be varied. It will be noted that there is a limit to the possible upward position of the rod 115, said limiting position being shown in Fig. 16.

After the shrinking operation has been completed the carrier is rotated to move the work-holder into a position above the trimming station and there moved down to trim the surplus material from the attaching face of the heel and to cut off the small projection from the bottom of the cover. The downward movement of the carrier 51 (Fig. 31) not only accomplishes the results just named but also turns the valve 175 (Fig. 21) to closed position to shut off the suction and breaks the toggle joints, as shown in Fig. 24, so as to lower the vertical rod 115. In order to disconnect the suction and to break the toggle joints, a stop 259 (Fig. 24) is provided at the trimming station with which the lower ends of the slide rods 191, 255 contact when the head is moved down. In said figure the head has reached its lowermost position, and the rods 191, 255 have been pushed up to cut off the suction from the port 117 and to lower the rod 115.

At this trimming station, there is a support 261 (Fig. 25) for the covered heel, said support having a downwardly extending hollow stem 263 slidably mounted in spaced bearings formed in a casting 264, said stem being continually urged upward by a compression spring 265 as far as an adjustable collar 267 will permit and being held from rotation by a screw 269 which is threaded through the wall of the upper bearing and the end of which extends into a vertical slot in the stem of the support. The member 264 is fastened to the frame of the machine by four screw bolts 270, two of which appear in the figure. The left-

hand face of the casting 264 is inclined as shown, and between this inclined face and a vertical face on the frame is a wedge 271 which may be adjusted vertically by turning a screw 273 which is threaded into the top of the wedge and is held from longitudinal movement. In order that the small projection on the bottom of the cover 200 may be cut off and fall through the hollow stem when the carrier is moved down at the trimming station, the support 261 (see Fig. 27) has a central cylindrical socket in which is vertically slideable a small perforated block 275 supported by a spring 276. To opposite sides of the block are fastened the stems of two cutting members 277 of thin spring steel having their upper ends bent toward each other to provide cooperating blades having cutting edges, said edges being normally apart as shown. When now the carrier, with its heel 100 and shrunken cover 200, is moved down, the small projection 300 enters between the spaced edges of the members 277, and upon further downward movement of the carrier to the position shown in Fig. 25, the edges of the cutting members are brought together to cut off the small projection 300 which falls through the hollow stem. When the heel is pressed against the support 261, as shown in Fig. 25, not only is the small projection 300 cut off but the series of cutters 121 trim the surplus material from the attaching face of the heel by cutting through two thicknesses of cover material. It will be noted that each cutter is independently yieldable so that the sectional cutter can accommodate itself to the contour of the attaching face of the heel. At this station, too, the clamping fingers are swung out to inoperative position, out of contact with the cover material which has been trimmed off. To this end, a generally ring-shaped member 273 (Fig. 28) is fastened to the frame of the machine by screw bolts 281 in such position that the lower end of the carrier passes through the ring, said ring being provided with two inclined cams, one of which is indicated at 282, which engage the lower one of the two small pins 163 on two clamping fingers and swing all the fingers away from the sleeve 101 of the work-holder.

At the trimming station an attendant grasps the covered heel, holds it stationary while the work-holder rises, and then removes the covered heel. During the first part of the upward movement of the work-holder the surplus cover material which has been severed by the blades 21 is stripped off from the sleeve 101 of the work-holder by the following mechanism. A stripping sleeve 286 is mounted for vertical sliding movement on the sleeve 101 of the work-carrier, said sliding sleeve being normally held up in the position shown by a compression spring 288. The lower end of this spring rests upon two diametrically opposite projections which are rigid with the sleeve 101 and extend through vertical slots in the sliding sleeve 286, one being shown at 290. These projections also act as cams in that their outer ends run on a cam face on a latch later to be described. The upper end of the spring 288 engages the under side of an annular flange or flat ring 283 which is rigid with the sliding sleeve 286. The sliding sleeve is thus held, at all times, stationary with respect to the sleeve 101 except at the trimming station. In order to cause the sliding sleeve 286 to be held down for an interval at the trimming station while the sleeve 101 is rising and thus to cause the sliding sleeve 286 to strip off the severed portion of the

cover 200 which has been shrunk about the lower end of the sleeve 101, two latches, one of which is indicated at 292, are provided. These latches are mounted at diametrically opposite points on the ring 279. Each latch has a notch to receive the ring 298 on the sliding sleeve 286 when the latch is permitted, as is shown in the figure, to occupy its operative position, and when the latches are thus operative, the sliding sleeve 286 is held from movement and will strip off the surplus material of the cover when the work-holder, with the sleeve 101 is raised. The two latches and the manner in which they are mounted are alike, and consequently only one will be described. The latch 292 is pivoted at its lower end at 294 between small ears carried by the ring 278; and a small spring 296 urges the latch to swing toward the sliding sleeve 286. This spring is wound about the pivot 294, one end engaging the ring 278 and the other end being bent around the back of the latch 292. The front of the latch 292 (the edge of the latch which confronts the sliding sleeve 286) is formed as a cam face, the highest locality on this face being the locality where the notch is located to receive the ring or flange 298 on the sliding sleeve 286. The projection 290 on the sleeve 101 has a curved outer end which engages the cam face 392 on the front edge of the latch, said outer end being too large to be received in the notch in the latch. When the work-holder moves down, the clamping fingers 105 are swung out by the cams 282 (Fig. 28), and, during this downward movement the projections 290 on the sleeve 101 ride down the cam faces on the edges of the latches, with the result that the latches are first swung out into inoperative positions and then, as the projections 290 approach the lower ends of the cam faces, are allowed to swing in so that the flange 298 on the sliding sleeve 286 is received in the notches in the latches. By this time the surplus material of the heel cover has been severed, and the parts are in the positions shown in Figures 25 and 28. When now the work-holder rises, the sliding sleeve 286 is held stationary for an interval and strips off the severed surplus material of the heel cover. After the stripping off of the surplus material, further upward movement of the work-carrier first causes the projections 290 to swing the latches out to inoperative position and later permits the clamping fingers 105 to swing back into their normal positions, as shown for example in Figures 1 and 5.

Referring now more particularly to Figs. 26, 29 and 30, the mechanism for rotating the spider 59, and with it the work-holders intermittently through ninety degrees, and for reciprocating the small shaft 53, and with it the work-holders, during the pauses between the intermittent movements of rotation will be described. The hub of the spider 59 is fast to a hollow shaft 283 in which the small shaft 53 is slideable, said shaft 283 being rotatably mounted in a stationary bearing sleeve 284. The upper end of the sleeve is integral with the plate 224 which, as has been stated, is bolted to the top of the frame; and upon the upper end of the sleeve rests the hub of the spider 59. To the lower end of the shaft 283 (Fig. 30) is fastened the hollow hub of a large gear 285. This large gear meshes with a small gear 287 which is loose upon but may be connected to a continuously rotating upright shaft 289, said shaft extending to the bottom of the machine and being rotatably mounted in spaced bearings 291 carried by the frame of the machine. The shaft 289 has

fast to its lower end a large gear 293 which meshes with a small gear 295 on an upright shaft 297, said shaft having fast to it a worm gear 299 which meshes with a worm 301 on a horizontal shaft 303, said last-named shaft being driven through a friction clutch by an alined, horizontal driving shaft 305 which is rotated by a belt 307 from a pulley 309 to which power is applied continuously from a suitable source.

Referring now to Fig. 29, the driving shaft 305 carries at its left-hand end one member 311 of a friction clutch, the other member 312 being carried by the shaft 303. A compression spring 304 normally holds the members of the clutch in engagement, as shown. The clutch may be disengaged by depressing a treadle 313 (Fig. 30) the hub of which is fastened to a rockshaft 315. To this rockshaft is also fastened the hub of a small arm 317 (Fig. 29), the upper end of which is pivoted to one end of a link 319, the other end of which is pivoted to the upper end of an arm 321 the hub at the lower end of which is fastened to a rockshaft 323. The hub of a substantially upright arm 326 is fastened to the far end of this rockshaft, the upper end of the arm having a fork carrying small rolls, one being shown at 327, which run in an annular groove formed in the hub of the conical member 312 of the friction clutch. With this construction depressing the treadle 313, by rocking the arm 326 counterclockwise about the axis of the rockshaft 323, will disconnect the clutch. The treadle may be locked in lowered position by swinging in a counterclockwise direction a small bell-crank lever 329 (Fig. 30) which is pivoted at 331 to the frame of the machine.

When the machine is thus at rest, it is sometimes convenient to be able to rotate the shaft 303 by hand, and to this end the following mechanism is provided. Referring first to Fig. 29, a downwardly extending arm 325, the hub of which is fastened to the near end of the rockshaft 323, is pivoted at its lower end to a long link 333, the other end of which is slideable through a sleeve in the lower end of a second clutch-shifting arm 335 having at its upper end a fork provided with small rolls, one being shown at 337, which run in an annular groove in the hub of a small spiral gear 339. The arm 335 is fulcrummed about a stationary pin 341, and the link 333 is continually urged to the left by a compression spring 343. The hub of the small gear 339, which is loose on the shaft 303, has small projections or ribs 345, spaced apart 90° (Fig. 33), which may be received in similarly arranged recesses, one being shown at 347 (Fig. 29), formed in a collar 349 which is fastened on the reduced end of the shaft 303. It will be evident that when the treadle 313 (Fig. 30) is raised, so that the clutch members 311, 312 are in engagement and the shaft 303 is being rotated, the small gear 339 is not rotatively connected to the shaft; but when the treadle is depressed, to disconnect the clutch members 311, 312, the small gear 339 is rotatively connected to the shaft 303. In order to be able to turn this gear by hand, a hand crank 351 (Fig. 30) is provided. The hub of this crank is fast to the outer end of a small horizontal shaft 353 which is rotatable in a bearing carried by the frame of the machine, the inner end of the shaft having fast to it a spiral pinion 355 which meshes with a small spiral gear 357 fastened to the upper end of an obliquely extending rotary shaft 359 to the lower end of which is fastened a small spiral pinion 361

which meshes with the spiral gear 339. Thus when the treadle 313 is held down so that no power is being applied to the shaft 303, said shaft may be rotated by hand.

5 The mechanism which has just been described serves to rotate the upright shaft 289 (Fig. 30) continuously when the treadle is in raised position; and rotation of this shaft, through mechanism which will now be described, is caused to 10 rotate the hollow shaft 283 intermittently through ninety degrees, thereby causing intermittent rotation of the spider 59 to move the work-holders through ninety degrees, and, during the pauses in the intermittent rotation, to 15 reciprocate the small shaft 53 and thereby the work-holders. The small gear 287 causes the rotation, and a barrel cam 363, which, like the gear, is loose upon the rotating shaft 289 but may be connected to it, causes the reciprocation, 20 these two members being alternately connected to the rotating shaft 289. The gear 287 is held from downward movement on the shaft by a collar 365 which is pinned to the shaft and by the bearing 291 upon which the hub of the gear rests. 25 This gear has integral with it a downwardly extending sleeve 367, having fast to its lower end the upper member 369 of a clutch, the lower member of which is a spool 373 which is splined to the shaft and therefore rotates with it and 30 can be moved longitudinally of the shaft. The upper clutch member 369 has recesses on its under side spaced 90° apart, one being shown at 375, in which may be received similarly arranged ribs 377 formed on the upper side of the spool 373. The spool 373 is shown as occupying its 35 lowermost position in which the clutch members are not connected and the small gear 287 is not being rotated. The barrel cam 363, which is held from longitudinal movement between two of the 40 spaced bearings 291, has a downwardly extending sleeve to which is splined for vertical sliding movement a second spool 379 which forms the upper member of a second clutch, the lower member 381 of which is pinned to the shaft 289. The 45 spool 379 has on its under side projections or ribs spaced 90° apart, one being shown at 383, which may be received in similarly arranged recesses formed in the upper side of the lower clutch member 381. In the position of parts shown, the 50 two clutch members are in engagement, and the small upright shaft 53, at the upper end of which the work-holders are supported, is about to be pulled down. The two spools 373 and 379 are 55 moved in unison alternately up, to cause one revolution of the small gear 287 and thereby a quarter revolution of the large gear 285 whereby the work-holders move through ninety degrees, and then down to cause one revolution of the barrel cam 363 to move the work-holders down and then up. In the cam track of the barrel cam 363 runs a small roll 385, carried by one end of an arm, the other end of which is fast to the far end of 60 a small rockshaft 387 mounted in a stationary bearing in the frame. On the near end of the rockshaft is fastened one end of a long arm 389 to the other end of which is pivoted the lower end of an upright link 391 the upper end of which is pivoted to one end of an arm 393, said arm being pivoted at its other end at 395 to the frame of the machine. The arm 393 has a fork carrying two small rolls which run in a horizontal slot 397 in a collar 399, said collar being fast to the lower end of the small reciprocable 65 up-right shaft 53.

Turning now to the two clutch spools 373, 379, the mechanism for moving them in unison up and down at intervals will be described. The upper spool 373 is carried by small rolls which extend into the annular groove in the spool, said rolls being carried by the branches of a forked arm 401, the hub of which is slideable along the axis of a small upright shaft 403 having fast to its lower end a gear 405 which is driven by a gear 407 of one-half the diameter of the gear 405, said gear 407 being fast to the upright shaft 289. The hub of the horizontal arm 401 has upon its upper side a small cam block 409 adjustably fastened to it by means of a set screw 410 which engages a downwardly projecting sleeve of the block. The arm 401, with its cam block 409, is urged continually upward by a compression spring 411 which rests upon one of the spaced bearings of the shaft 403. Pinned to the shaft above the cam block 409 is a cam 413 against the underside of which the cam block 409 is held. In the angular position shown of the cam 413, the cam block 409 is being held down by the cam 413. The arm 401 is, therefore, being held down and the small gear 287 is not turning. By the time that the upright shaft 403 has finished half a revolution, the cam 413 will be in an angular position to permit the spring 411 to push up the arm 401 and thereby connect the small gear 287 to the upright rotating shaft 289. The lower spool 379 is carried by a forked arm 415 like the forked arm 401 which carries the upper spool 373. The hub of the arm 415 is mounted for vertical sliding movement like the arm 401 and has fast to it on its underside a cam block 417, the hub of the arm 415 with its cam block being continuously urged downward by a compression spring 419 so as to hold the cam block 417 in contact with a cam 421 which is pinned to the upright shaft 403 and rotates with it. The cam block 417 and the cam 421, like the cam block 409 and its cooperating cam 413, have complementally shaped adjacent faces. With the parts in the positions shown, the cam block 417, and with it the arm 415, has been pushed down to its lower position so that the spool 379 has connected the barrel cam 363 with the rotating shaft 289. Assuming that the parts are shown in the positions which they occupy when the small gear 287 has just been disconnected from the shaft and the barrel cam 363 has just been connected with said shaft, the rotation of the barrel cam will continue until it has completed one revolution. This will swing the lever 389 down and then up, the cam track being so shaped that there is a short dwell when the lever has swung to its lowest position. The small upright shaft 403 will then have completed a half revolution, at which time the lower cam 421 will push up the lower arm 415 to disconnect the barrel cam 363 from the rotating shaft 289, and the upper cam 413 will permit the spring 411 to push the arm 401 up to connect the gear 287 with the shaft 289 whereupon the large gear 285 will be rotated a quarter revolution. The arms 401, 415 will then be pushed down to the positions shown to disconnect the gear 287 and to cause another rotation of the barrel cam.

With the treadle 313 (Fig. 30) in raised position, the machine runs continuously to cause the work-holders to descend into cooperative relation each with one of the stations, then to dwell for a short interval in their lowermost positions, then to rise, then to be rotated through 90° into regis-

ter with the next succeeding stations, and to repeat these movements. The operator presents heels to the first station and shrinkable covers to the second station. The work-holders in succession pick up a heel at the first station, place it in a cover at the second station, lower the heel with its cover into the shrinker at the third station and trim the surplus material from the upper part of the cover as well as cause the projection at the bottom of the cover to be cut off at the fourth station. At this last station an attendant removes the covered heels.

In Fig. 32 there is shown part of a modified machine which is like the machine described above except that the ports 177 in the radial arms 47 are at all times in communication with the ports 117 in the small upright rods 115. The construction shown in Fig. 32 is like that shown in Fig. 21 except that the valve 175 of Fig. 21 and the mechanism for operating it are not present, the port 177 being at all times in communication with the port 117 through the flexible tube 176. In case the construction shown in Fig. 32 is employed, the suction is effective to produce a partial vacuum in the cover only at the shrinking station, the capacity of the pump 58 being sufficient to produce the desired partial vacuum despite the fact that the ports in the other three rods at the other three stations are open to the atmosphere. The operation of the modified machine is the same as that of the machine first described above, except that air is being sucked at all times through all the air conduits.

Although the invention has been set forth as embodied in a machine in which four operations are performed upon each article, it should be understood that the invention is not limited in the scope of its application to the particular machine which has been shown and described nor to the performance of all of the operations.

In application for Letters Patent of the United States, Serial No. 398,773, filed June 19, 1941, in my name, there is disclosed a machine for shrinking a cover upon an article, and all subject matter common to the prior application and to the present one is claimed in said prior application.

Having thus described the invention, what I claim as new and desire to secure by Letters Patent of the United States is:

1. A machine for covering an article, said machine having in combination a work-holder having means for clamping to it the mouth of a shrinkable cover containing an article about which the cover is to be shrunk and article-engaging means, a shrinker, means for producing relative movement of approach between the shrinker and the work-holder to cause the cover to be shrunk, suction means for creating a partial vacuum in the cover, and mechanical means for moving the article-engaging means toward the rest of the work-holder, said last-named two means acting during the shrinking of the cover.

2. A machine for covering an article, said machine having in combination a work-holder having means for clamping to it the mouth of a shrinkable cover containing an article and means for engaging the article, a shrinker, means for causing relative movement of approach between the shrinker and the work-holder to cause the cover to be shrunk, and means acting through the article-engaging member for moving the article away from the bottom and toward the mouth of the cover.

3. A machine for covering an article, said ma-

chine having in combination a work-holder having means for clamping to it the mouth of a shrinkable cover containing an article and means for engaging the article, a shrinker, means for causing relative movement of approach between the shrinker and the work-holder to cause the cover to be shrunk, means acting through the article-engaging member for moving the article away from the bottom and toward the mouth of the cover, and other means for creating a partial vacuum in the cover.

4. A machine for covering an article, said machine having in combination a carrier, a plurality of work-holders supported in spaced relation by said carrier, said work-holders having means for engaging an article and means for clamping the mouth of a shrinkable cover to the work-holder, a plurality of stations arranged in the same spaced relation as are the work-holders, said stations including a shrinking station provided with a shrinking agent and means for producing intermittent relative movements between the carrier and the stations to cause the work-holders to be alined successively with the stations and for producing relative movements of reciprocation during the pauses between the said intermittent alining movements, and means acting only at the shrinking station to create a partial vacuum in the cover.

5. A machine for covering an article, said machine having in combination a carrier, a plurality of work-holders supported in spaced relation by said carrier, said work-holders having means for engaging an article and means for clamping the mouth of a shrinkable cover to the work-holder, a plurality of stations arranged in the same spaced relation as are the work-holders, said stations including a shrinking station provided with a shrinking agent, and means for producing intermittent relative movements between the carrier and the stations to cause the work-holders to be alined successively with the stations and for producing relative movements of reciprocation during the pauses between the said intermittent alining movements, and means acting only at the shrinking station to move the article toward the mouth of the cover.

6. A machine for covering an article, said machine having in combination a carrier, a plurality of work-holders arranged radially about and supported in spaced relation by said carrier, said work-holders including an article-engaging member movable with respect to the rest of the work-holder, a plurality of stations arranged in the same radial and spaced relation as are the work-holders, said stations including a shrinking station, means for producing intermittent relative movements of rotation between the carrier and the stations to cause the work-holders to be alined successively with the stations and for producing relative movements of reciprocation during the pauses between the intermittent alining movements of rotation, and mechanism becoming operative at the shrinking station for moving said article-engaging member with respect to the rest of the work-holder of which it forms a part.

7. A machine for covering an article, said machine having in combination a carrier, a plurality of work-holders arranged radially about and supported in spaced relation by said carrier, said work-holders including an article-engaging member movable with respect to the rest of the work-holder, a plurality of stations arranged in the same radial and spaced relation as are the

work-holders, said stations including a shrinking station, means for producing intermittent relative movements of rotation between the carrier and the stations to cause the work-holders to be alined successively with the stations and for producing relative movements of reciprocation during the pauses between the intermittent alining movements of rotation, mechanism becoming operative at the shrinking station for moving said article-engaging member with respect to the rest of the work-holder of which it forms a part and means for adjustably varying the limits of movement of said article-engaging member.

8. A machine for covering an article, said machine having in combination a carrier, a plurality of work-holders supported in spaced relation by said carrier, said work-holders each including an article-engaging member movable with respect to the rest of the work-holder, a plurality of stations arranged in the same spaced relation as are the work-holders, said stations including a shrinking station, means for producing intermittent relative movements between the carrier and the stations to cause the work-holders to be alined successively with the stations and for producing relative movements of reciprocation during the pauses between the intermittent alining movements, toggle mechanisms, one for each work-holder, for raising and lowering said article-engaging members with respect to the rest of their respective work-holders, said toggle mechanisms being broken and the article-engaging members in their lower positions as the work-holders approach alinement with the shrinking station, and means operated by the relative movement of reciprocation between the carrier and the stations for straightening the toggle of the work-holder which is at the shrinking station.

40 9. A machine for covering an article, said machine having in combination a carrier, a plurality of work-holders supported in spaced relation by said carrier, said work-holders each including an article-engaging member movable with respect to the rest of the work-holder, a plurality of stations arranged in the same spaced relation as are the work-holders, said stations including a shrinking station, means for producing intermittent relative movements between the carrier and the stations to cause the work-holders to be alined successively with the stations and for producing relative movements of reciprocation during the pauses between the intermittent alining movements, said work-holders each having a port leading to its work-engaging end, a valve for admitting suction to said ports, said valves being closed as the work-holders approach the shrinking station, and means operated by the relative movement of reciprocation between the carrier and the stations for opening the valve at the shrinking station.

65 10. A machine for covering an article, said machine having in combination a carrier, a plurality of work-holders supported in spaced relation by the carrier, said work-holders having means for engaging an article and means for clamping the mouth of a shrinkable cover to the work-holders, a plurality of stations including a station at which the article is located properly in a cover and a shrinking station, and means for producing intermittent relative movements between the work-holders and the stations to cause the work-holders to be alined successively with the stations and for producing relative movements of reciprocation during the pauses be-

tween the intermittent alining movements, said means comprising a hollow rotary shaft, a rod slidable in the hollow shaft, means for rotating the shaft intermittently and means for reciprocating the rod in the pauses between the intermittent rotative movements.

11. A machine for covering an article, said machine having in combination a carrier, a plurality of work-holders supported in spaced relation by the carrier, said work-holders having means for engaging an article and means for clamping the mouth of a shrinkable cover to the work-holders, a plurality of stations including a station at which the article is located properly in a cover and a shrinking station, and means for producing intermittent relative movements between the work-holders and the stations to cause the work-holders to be alined successively with the stations and for producing relative movements of reciprocation during the pauses between the intermittent aligning movements, said means comprising a hollow rotary shaft, a rod slidable in the hollow shaft, a constantly rotating shaft, and means for connecting the hollow shaft alternately first with the hollow shaft and then with the reciprocable rod.

12. A machine for covering an article, said machine having in combination a carrier, a plurality of work-holders supported in spaced relation by the carrier, said work-holders having means for engaging an article and means for clamping the mouth of a shrinkable cover to the work-holders, a plurality of stations including a station at which the article is located properly in a cover and a shrinking station, and means for producing intermittent relative movements between the work-holders and the stations to cause the work-holders to be alined successively with the stations and for producing relative movements of reciprocation during the pauses between the intermittent aligning movements, said means comprising a hollow rotary shaft, a rod slidable in the hollow shaft, a constantly rotating shaft, a gear on said constantly rotating shaft which may be connected to and disconnected from said shaft, a gear on the hollow shaft meshing with the gear on the constantly rotating shaft, a cam on the constantly rotating shaft which may be connected to and disconnected from said constantly rotating shaft, reciprocating mechanism for the rod operated by rotation of the cam and means for connecting alternately first the gear and then the cam with the constantly rotating shaft.

13. A machine adapted to turn the surplus material from the upper portion of a cover which has been shrunk about an article, said machine having in combination a work-holder, a trimming cutter comprising independently yieldable sections, a support for the covered article, and means for producing relative movement of approach between the work-holder and the support.

14. A machine adapted to cut off from the bottom of a cover, which has been shrunk about an article, a small projection, said machine having in combination a work-holder, a support for a covered article, and means for producing relative movement of approach between the work-holder and the support, said support including a pair of cooperating blades normally spaced apart to receive between them the projection and means operated by the work in the course of the relative movement for causing the blades to sever the projection.

15. A machine having in combination a member for holding an article about which and about one end of the member a cover has been shrunk, means for severing the cover whereby surplus material remains on the member, and means for engaging the edge of the severed surplus material and stripping it from the member.

16. A machine for covering an article, said machine having in combination, a plurality of stations arranged in spaced relation about a circle, a plurality of work-holders similarly arranged about a circular path, means for imparting intermittent movements of rotation to the work-holders to aline them successively with successive stations, and means for reciprocating the work-holders during the pauses between the intermittent movements of rotation, one of said stations including the support for a piece of work, means whereby the support may be adjusted along the line of reciprocation and means whereby said support may be adjusted in the general direction of the path of rotation.

17. A machine for covering an article, said machine having in combination a carrier, a plurality of work-holders supported in spaced relation by said carrier, said work-holders having means for engaging an article, means for clamping the mouth of a shrinkable cover to the work-holder and means for trimming a shrunken cover, a plurality of stations arranged in spaced relation, said stations including a station for supporting an article to be engaged and picked up by relative reciprocation of the station and a work-holder which is alined with it, a placing station for supporting a hollow, shrinkable cover in position to receive an article held by a work-holder upon relative reciprocation of the station and a work-holder which is alined with it, said station including means responsive to said relative reciprocation for causing the clamping means to clamp the mouth of a cover to a work-holder, a shrinking station including a receptacle containing a shrinking agent to the action of which a cover, containing an article, with the mouth of the cover clamped to a work-holder, may be subjected by relative reciprocation of the station and a work-holder which is alined with it and a trimming station adapted, by relative reciprocation between it and a work-holder which is alined with it, to cooperate with the trimming means, and means for producing relative intermittent movements between the work-holders and the stations to cause the work-holders to be alined successively with the stations and for producing relative movements of reciprocation during the pauses between the intermittent alining movements.

18. A machine for covering an article, said machine having in combination a carrier, a plurality of work-holders supported in spaced relation by said carrier, said work-holders having means for engaging an article, means for clamping the mouth of a shrinkable cover to the work-holder and means for trimming a shrunken cover, a plurality of stations arranged in spaced relation, said stations including a station for supporting an article to be engaged and picked up by relative reciprocation of the station and a work-holder which is alined with it, a placing station for supporting a hollow, shrinkable cover in position to receive an article held by a work-holder upon relative reciprocation of the station and a work-holder which is alined with it, said station including means responsive to said relative reciprocation for causing the clamping means to clamp

the mouth of a cover to a work-holder, a shrinking station including a receptacle containing a shrinking agent to the action of which a cover, containing an article, with the mouth of the cover clamped to a work-holder, may be subjected by relative reciprocation of the station and a work-holder which is alined with it and a trimming station adapted, by relative reciprocation between it and a work-holder which is alined with it, to cooperate with the trimming means, means for producing relative intermittent movements between the work-holders and the stations to cause the work-holders to be alined successively with the stations and for producing relative movements of reciprocation during the pauses between the intermittent alining movements, and means for producing a partial vacuum in the cover during the shrinking operation.

19. A machine for covering an article, said machine having in combination a carrier, a plurality of work-holders supported in spaced relation by said carrier, said work-holders having means for engaging an article and means clamping the mouth of a shrinkable cover to the work-holder, a plurality of stations arranged in spaced relation, said stations including a station for supporting an article to be engaged and picked up by relative reciprocation of the station and a work-holder which is alined with it, a placing station for supporting a hollow, shrinkable cover in position to receive an article held by a work-holder upon relative reciprocation of the station and a work-holder which is alined with it, said station including means responsive to said relative reciprocation for causing the clamping means to clamp the mouth of a cover to a work-holder and a shrinking station including a receptacle containing a shrinking agent to the action of which a cover, containing an article, with the mouth of the cover clamped to a work-holder, may be subjected by relative reciprocation of the station and a work-holder which is alined with it, and means for producing relative intermittent movements between the work-holders and the stations to cause the work-holders to be alined successively with the stations and for producing relative movements of reciprocation during the pauses between the intermittent alining movements.

20. A machine for covering an article, said machine having in combination a carrier, a plurality of work-holders supported in spaced relation by said carrier, said work-holders having means for engaging an article and means clamping the mouth of a shrinkable cover to the work-holder, a plurality of stations arranged in spaced relation, said stations including a station for supporting an article to be engaged and picked up by relative reciprocation of the station and a work-holder which is alined with it, a placing station for supporting a hollow, shrinkable cover in position to receive an article held by a work-holder upon relative reciprocation of the station and a work-holder which is alined with it, said station including means responsive to said relative reciprocation for causing the clamping means to clamp the mouth of a cover to a work-holder and a shrinking station including a receptacle containing a shrinking agent to the action of which a cover, containing an article, with the mouth of the cover clamped to a work-holder, may be subjected by relative reciprocation of the station and a work-holder which is alined with it, means for producing relative intermittent movements between the work-holders and the stations to cause

the work-holders to be alined successively with the stations and for producing relative movements of reciprocation during the pauses between the intermittent alining movements, and means for producing a partial vacuum in the cover during the shrinking operation.

21. A machine for covering an article, said machine having in combination a carrier, a plurality of work-holders supported in spaced relation by said carrier, said work-holders having means for engaging an article, means for clamping the mouth of a shrinkable cover to the work-holder and means for trimming a shrunken cover, a plurality of stations arranged in spaced relation, said stations including a placing station for supporting a hollow, shrinkable cover in position to receive an article held by a work-holder upon relative reciprocation of the station and a work-holder which is alined with it, said station including means responsive to said relative reciprocation for causing the clamping means to clamp the mouth of a cover to a work-holder, a shrinking station including a receptacle containing a shrinking agent to the action of which a cover, containing an article, with the mouth of the cover clamped to a work-holder, may be subjected by relative reciprocation of the station and a work-holder which is alined with it, to cooperate with the trimming means, and means for producing relative intermittent movements between the work-holders and the stations to cause the work-holders to be alined successively with the stations and for producing relative movements of reciprocation during the pauses between the intermittent alining movements.

22. A machine for covering an article, said machine having in combination a carrier, a plurality of work-holders supported in spaced relation by said carrier, said work-holders having means for engaging an article, means for clamping the mouth of a shrinkable cover to the work-holder and means for trimming a shrunken cover, a plurality of stations arranged in spaced relation, said stations including a placing station for supporting a hollow, shrinkable cover in position to receive an article held by a work-holder upon relative reciprocation of the station and a work-holder which is alined with it, said station including means responsive to said relative reciprocation for causing the clamping means to clamp the mouth of a cover to a work-holder, a shrinking station including a receptacle containing a shrinking agent to the action of which a cover, containing an article, with the mouth of the cover clamped to a work-holder, may be subjected by relative reciprocation of the station and a work-holder which is alined with it, to cooperate with the trimming means, and means for producing relative intermittent movements between the work-holders and the stations to cause the work-holders to be alined successively with the stations and for producing relative movements of reciprocation during the pauses between the intermittent alining movements, and means for producing a partial vacuum in the cover during the shrinking operation.

23. A machine for covering an article, said machine having in combination a carrier, a plurality of work-holders supported in spaced relation by said carrier, said work-holders having

means for engaging an article and means for clamping the mouth of a shrinkable cover to the work-holder, a plurality of stations arranged in spaced relation, said stations including a placing station for supporting a hollow shrinkable cover in position to receive an article held by a work-holder upon relative reciprocation of the station and a work-holder which is alined with it, said station including means responsive to said relative reciprocation for causing the clamping means to clamp the mouth of a cover to a work-holder and a shrinking station including a receptacle containing a shrinking agent to the action of which a cover, containing an article, with the mouth of the cover clamped to a work-holder, may be subjected by relative reciprocation of the station and a work-holder which is alined with it, and means for producing relative intermittent movements between the work-holders and the stations to cause the work-holders to be alined successively with the stations and for producing relative movements of reciprocation during the pauses in the intermittent alining movements.

24. A machine for covering an article, said machine having in combination a carrier, a plurality of work-holders supported in spaced relation by said carrier, said work-holders having means for engaging an article, means for clamping the mouth of a shrinkable cover to the work-holder and means for trimming a shrunken cover, a plurality of stations arranged in spaced relation, said stations including a shrinking station comprising a receptacle containing a shrinking agent to the action of which a cover, containing an article, with the mouth of the cover clamped to a work-holder, may be subjected by relative reciprocation of the station and a work-holder which is alined with it and a trimming station adapted, by relative reciprocation between it and a work-holder which is alined with it, to cooperate with the trimming means, and means for producing relative intermittent movements between the work-holders and the stations to cause the work-holders to be alined successively with the stations and for producing

relative movements of reciprocation during the pauses between the intermittent alining movements.

25. A machine for covering an article, said machine having in combination a carrier, a plurality of work-holders supported in spaced relation by said carrier, said work-holders having means for engaging an article and means for clamping the mouth of a shrinkable cover to the work-holder, a plurality of stations arranged in spaced relation and adapted upon relative reciprocation between them and work-holders which are alined with them to cooperate with the work-holders, said stations including a shrinking station where a cover is shrunk about an article, unobstructed conduits leading from the work-engaging ends of the work-holders, a suction pump for continually drawing air through all the conduits simultaneously, and means for producing relative intermittent movements between the work-holders and the stations to cause the work-holders to be alined successively with the stations and for producing relative movements of reciprocation between the pauses between the intermittent alining movements.

26. A machine for covering an article, said machine having in combination a carrier, a plurality of work-holders supported in spaced relation by said carrier, said work-holders having means for engaging an article and means for clamping the mouth of a shrinkable cover to the work-holder, a plurality of stations, including a placing station and a shrinking station, arranged in spaced relation and adapted upon relative reciprocation between them and work-holders which are alined with them to cooperate with the work-holders, and means for producing relative intermittent movements between the work-holders and the stations to cause the work-holders to be alined successively with the stations and for producing relative movements of reciprocation during the pauses between the intermittent alining movements.

CERTIFICATE OF CORRECTION.

Patent No. 2,328,695.

September 7, 1943.

ALEXIS E. USHAKOFF.

It is hereby certified that error appears in the printed specification of the above numbered patent requiring correction as follows: Page 5, second column, line 57, for "rod" read --roll--; page 11, second column, line 18, claim 16, for "the" read --a--; page 12, second column, line 58, claim 22, strike out "machine having in combination a carrier, a plu--" and insert instead -- the cover clamped to a work-holder, may be sub- --; and that the said Letters Patent should be read with this correction therein that the same may conform to the record of the case in the Patent Office.

Signed and sealed this 30th day of November, A. D. 1943.

(Seal)

Henry Van Arsdale,
Acting Commissioner of Patents.
